John Nelling Farrar

UNITED STATES PATENT OFFICE.

JOHN NUTTING FARRAR, OF NEW YORK, N. Y.

MECHANISM FOR SEPARATING TEETH.

SPECIFICATION forming part of Letters Patent No. 425,067, dated April 8, 1890.

Application filed June 4, 1889. Serial No. 313,102. (No model.)

To all whom it may concern:

Be it known that I, JOHN NUTTING FARRAR, a citizen of the United States, residing in the city of New York, county and State of New

5 York, have invented new and useful improvements in adjustable apparatus to aid dentists in operating upon the teeth—viz., Mechanism for Separating Teeth; and I hereby declare that the following specification is a sufficiently clear description thereof to enable other persons skilled in the art to make and use the same, reference being had to the accompanying drawings.

15 My invention has for its object the easy separation of teeth and the retaining of the rubber dam to facilitate the operation of plugging cavities in teeth. I attain these objects by the improved mechanism illustrated in the accompanying drawings, which 20 belong to and constitute a portion of this specification, and in which—

Figure 1 is a perspective view of the mechanism. Fig. 2 is a view of parts detached. Fig. 3 is a view of one of the levers, the other 25 being shown in Fig. 2; and Fig. 4 is a view of said levers pivoted together, parts being broken away.

The apparatus is preferably made of steel or other metal nickel plated, and includes a 30 device having two arms or levers A A', pivoted together like an ordinary pair of tailor's shears. The arms A A' are provided near their adjacent extremities at one end with apertures to receive detachable separating 35 clamps. These are indicated by the letters C, C', and P, and are provided with suitable dowel-like projections or pins to fit said apertures, or with equivalent fastening devices, and they are variously shaped to adapt them to 40 different positions or conformations of teeth. The opposite extremities K K'' of the device are provided, the former with a groove G and the latter with a rib K', to fit, respectively, a groove and rib formed on the edges of a wedge-shaped piece, which latter fits loosely on a 45 screw S, flattened at one end and perforated to receive the pivot that passes through A A'. A screw-nut T on the rod S is provided for forcing the wedge toward the pivot and 50 spreading the ends K K'', thereby in operation causing the clamps fitted in or on the opposite ends of A A' to securely embrace

any object lying between them, as will be readily understood.

J J' indicate different forms of holes to receive various clamps or separators.

I denotes a gum-guard which is adapted to be screwed into a suitable hole in one of the members A or A', and when in use rests upon the opposing surface of the tooth to prevent the creeping down of the clamps upon the gum, and thereby causing pain to the patient.

I' is a similar guard screwed into an arm A and used for a like purpose, but made longer and so bent that the free extremity 65 will rest loosely in a hole in the opposite arm, and I'' is a guard on arm A, having a loop to engage the end of an arm A or A'.

As shown, the ends of the arms A A' are provided with holes of different shapes. A 70 section of similar arms provided with apertures for receiving the clamp-separators is shown at F in Fig. 2.

C' indicates a clamp provided with an extension L, that can be inserted in a corresponding aperture.

Of the devices for holding the wedge in the proper plane I prefer a pin such as illustrated combined with a spring-loop F'. The latter device is very efficient, but is liable under 80 some conditions to be in the way. It can be applied to either side K or K'' of the implement. The wedge W can be entirely removed from the screw. It can also be turned to engage the pin with an opposite side, if such 85 side is suitably grooved. With such devices as the pins or as the spring-loop it is not necessary to provide ribs and grooves on the faces of the wedge and parts K K'', as they will hold the wedge in the proper plane and 90 obviate any tendency to turn about the screw that is to rotate about its axis.

I am aware that various devices for separating teeth and detachable clamps that slip like ferrules over arms have been proposed 95 by others, and devices of this character are not broadly of my invention.

Having thus described my invention, what I claim, and desire to secure by Letters Patent, is as follows:

1. The device for holding separators or clamps, consisting of two pivoted members having apertures at one end to receive said clamps and mechanism consisting of a wedge-

shaped piece, a screw-bolt passing therethrough and secured between said members or arms, and a nut fitted to screw upon the bolt and jam the wedge between the arms to force toward each other their opposite ends and the clamps secured therein, substantially as described.

2. In combination with the pivoted arms, the wedge provided with a groove and a rib, the arms being correspondingly grooved and ribbed, substantially as described.

3. The combination of the pivoted arms, the clamping-pieces, a gum-guard, and mechanism for forcing the clamping-pieces upon the teeth, substantially as described.

4. The combination of the pivoted arms with the clamps, gum-guards, grooved and ribbed wedge, screw, and wedge-operating nut working on the screw, substantially as described.

5. In combination with the arms pivoted to each other and adapted to receive clamps at one end thereof, the wedge W, situated at the opposite end, and mechanism for forcing the wedge toward the pivot, substantially as described.

JOHN NUTTING FARRAR.
